UNITED STATES PATENT OFFICE.

JULIAN O. ELLINGER, OF NEW YORK, N. Y.

UNIT-BAR FOR CONCRETE CONSTRUCTION.

No. 890,032.

Specification of Letters Patent.

Patented June 9, 1908.

Application filed September 18, 1906. Serial No. 335,112.

To all whom it may concern:

Be it known that I, JULIAN O. ELLINGER, a citizen of the United States, and residing in the city of New York, county of New York, and State of New York, have invented certain new and useful Improvements in Unit-Bars for Concrete Construction, of which the following is a specification.

Because of many well known advantages thereof over masonry and other building materials, concrete, beton and like plastic compositions are now commonly used in building walls, floors etc. Such material is capable of withstanding enormous compression strains, but has little power of resistance to tension and shearing stresses. It is therefore common to reinforce them against such stresses by embedding metal therein in the process of molding the concrete to form the article intended, such as a beam, a girder or the like. Unit bars are commonly or frequently used as the reinforcing element in these composite structures and the present invention relates to such bars.

It has for its principal aim the provision of a unit bar which will have maximum efficiency.

In the accomplishment of the aim herein set forth, I have provided a unit bar which has a plurality of longitudinally extending tensile members connected with each other and held in proper relation at all times by a series of elements which extend transversely of the bar and are bent intermediate of their ends to form straps or loops which open downward and have their free ends fixedly connected to the tension members. These elements rise from the tension members and connect the latter with each other. They assume shearing stresses and transmit strains to the tension members. They are so arranged as to engage the concrete between their limbs with their flat surfaces. When, as in the form herein shown and preferred, they are made integral with the tension members, it is of great advantage that the web connecting the tension members with each other be cut crosswise to produce these transverse elements, for the reason that by so forming them they may be of length adapted to inclose a considerable portion of the concrete in which the reinforcement is embedded and at the same time may be disposed closely together; it being apparent that if the metal from which

they are formed be cut lengthwise of the bar or blank, their number will depend upon the number of times which their length will go into the bar, so that if made long enough to extend around the main part of the concrete their distance apart will be too great and their number too few effectually to support the reinforcement on the main body of the concrete and to reinforce the latter, which functions they subserve in the present structure. Their action is supplemented by other projecting members, each of which is attached to a tension member at one end and has its other end free. These supplemental members may project from the tension members, at different angles with relation thereto than do the loops or stirrups, hereinbefore referred to. In addition to the foregoing elements, the bar is also provided at predetermined places with other projections which respectively extend horizontally and vertically therefrom, or approximately so, and are adapted to engage the sides and bottom of the mold and serve the purposes of stops or guides to determine the proper position of the bar in the mold and supports to hold it in such position during the formation of the beam or other article being made, and in the finished article.

The construction of unit bar hereinbefore generally described not only has the advantages indicated, but it lends itself very readily to a mode of producing the same from one piece of metal, which mode is hereinafter described.

My invention consists in certain peculiarities in the construction and arrangement of parts and in certain novel combinations of elements substantially as hereinafter described and particularly pointed out in the subjoined claims.

The accompanying drawings illustrate preferred embodiments of the invention, and in said drawings: Figure 1 is a plan view of the blank from which the unit bar is produced, said blank being shown in the form which it has in the initial stage of the manufacture. Fig. 2 is an end view of the same. Fig. 3 is a plan view of the blank in its finished form, that is to say, after it has been cut, but before it has been compressed to produce the finished bar. Fig. 4 is a perspective view of the completed unit bar made from the blank shown in Fig. 3. Fig. 5 is an end view of the same. Fig. 6 is a detail view, similar to Fig. 2, of a slightly modified form of the blank. Fig. 7 is a per-

spective view of the completed bar made from the blank shown in Fig. 6. Fig. 8 is a cross sectional view through a former containing the unit bar, showing the manner in 5 which the unit bar centers itself therein.

The same characters of reference designate the same parts in the several views.

I will first describe the preferred form of the unit bar in detail and will then set forth 10 one mode of its production, when all its parts are of integral formation.

The tension element has two members 1 and 2 which are located side by side and are connected with each other at intervals by 15 loops or stirrups 3. There may be any desired number of these loops or stirrups at each side of the longitudinal center of the bar and they preferably are inclined, and those at one side of the center of the bar are preferably inclined in a direction which is opposite to that of those at the other side of said center. As already indicated said loops serve to connect the tension members or bars 1 and 2 with each other and hold the same in 20 proper relative position, and support the bars by their engagement with the main body of concrete, which they encircle, and moreover act efficiently to resist the shearing strain to which the article is subjected in use and efficiently transmit stresses into the tension member 1 and 2. Their number, position and inclination may vary with different requirements of use, it being especially to be noted that the construction of the bar is such 25 that these loops or stirrups 3 may be of any desired number and arranged at any desired distance apart, within the limits of the bar, and extend at any desired angle or angles with respect to each other and to the tension members 1 and 2. The unit bar further comprises additional projecting elements 4, hereinafter referred to as projecting strips, which extend from the respective tension bars 1 and 2, are spaced apart thereon and 30 project at any desired angle with relation thereto. These projecting strips may in some cases be dispensed with, the parts forming these strips being unsevered to form stirrups or loops. The unit bar is also provided 35 with what I herein term centering ears or lugs which project from the respective tension elements or bars 1 and 2. Of these ears some, as 5, extend laterally and others as 6, extend downwardly. They serve respectively to engage the sides and bottom of the form F in which the bar is placed preparatory to embedding the same in the concrete or other plastic material X; the lugs 5 centering the bar laterally and the lugs 6 centering the 40 same vertically. By this means accuracy in the positioning of the bar in the form and in the article is assured without requiring special attention on the part of the workman.

Having thus set forth the structure of the 45 unit bar, I will next proceed to describe one

way by which the same may be produced. The first step in the formation of the bar is the production of what may be termed an initial blank, as A (Figs. 1 and 2). This blank is of any suitable length and width and comprises a body or web and having its longitudinal edges in the form of bars a' a^2 . This blank is preferably formed by rolling and the bars a' a^2 are preferably circular in cross section, though any other form may be used. 70 The next step in the production of the unit bar is the removal from the web a portions a^3 of the metal thereof, leaving spaced strips b b' and tabs or ears c and c' . It is preferred, as shown, that the lines of removal be such 75 that each or all of the strips b b' formed thereby have a pair of limbs arranged diagonally to the longitudinal bars and joining each other at the transverse central line of the blank, toward which line the limbs converge, but any other formation may be made. 80

It will be apparent that the lines of the cut will depend upon and determine the number and position of the strips b b' and tabs c and c' left after the metal, a^3 , has been removed, 90 and this may be varied to suit different conditions of use. Thus, as shown in Fig. 3, the strips b b' are approximately V shaped with all their limbs arranged at an angle of approximately 45 degrees to the bars a' and a^2 95 and with those at one side of the longitudinal center of the blank pointing in one direction and those at the other side of said center pointing in the opposite direction; while in the form of blank A^{10} , shown in Fig. 6, the 100 lines of cut are such that some of the strips as b^{10} and b^{100} , are of approximately V form with their limbs at angles of 45 degrees to the bars a^{10} and a^{11} , others (as b^{11} and b^{110}) are of V form with the limbs at greater angles than 45 degrees, others (as b^{12} and b^{120}) are of V form with their limbs at lesser angles than 45 degrees, and still others (as b^{13} and b^{130}) extend directly across from one bar to the other. It is to be understood that this figure is merely 105 for the purpose of exemplifying some of many different forms of cuts which may be made to produce corresponding different shapes and arrangement of connecting strips, and that the arrangement shown is purely an arbitrary 110 one which may be varied at will. It will be seen that the blank now formed has within it the elements which constitute all the members of the unit bar hereinbefore referred to, 115 it being apparent that the bars a' and a^2 of the blank A, and the bars a^{10} and a^{11} of the blank A^{10} , form the tension elements of the respective unit bars; that the strips b and b' of the one form, and b^{10} , b^{100} , b^{11} , b^{110} , b^{12} , b^{120} , and b^{13} , b^{130} of the other form, are adapted to 120 form the loops and projecting strips of their respective forms of unit bars; and the tabs or ears c and c' constitute what in the finished 125 unit bars are the ears or lugs 5 and 6 by which the bars are centered and supported. 130

It should be noted that the strips as b' ; b^{100} , b^{110} , b^{120} and b^{130} , which are to constitute the projecting strips 4 of the one form, 4^a, of the other form of the unit bar, are severed at a suitable point, as for example at the junction of their converging or diverging members, as indicated in Figs. 3 and 4. This may be done at the same time the web is punched out on the dotted lines to form the strips and ears.

What may constitute the final step may now be performed. This step consists in subjecting the blank to lateral compression, whereby its longitudinal bars are brought closer together and the strips connecting the same are bent. It will be apparent that the strips, as b , b^{10} , b^{11} , b^{12} and b^{13} which connect the bars and which are not themselves cut or severed at any point, assume, when the bars are subjected to the lateral compression described, the loop or stirrup form, herein shown as of inverted V shape; while the remaining strips, which are severed as described, essentially assume a different angle, their elements separating from each other due to the severance thereof. It is to be understood that in some forms of my unit bar the strip b' may not be severed to form the supplement strip 4. When not severed they form loops or stirrups when the tension bars are moved towards each other. This compression step is carried out on a suitable former adapted to the purpose and preferably by a machine or apparatus which is adapted to press both sides of the blank toward each other. At a proper time, and this may be during the compression step just described, the lugs or ears c and c' are bent in different directions properly to form the centering and supporting guides 5 and 6 described. By these operations I have provided a unit bar having the characteristic features set forth; that is to say I have provided a reinforcing bar for concrete and other compositions or materials, which comprises a plurality of tension members, loops connecting the same, projecting strips, extending from the tension members and having a different angle from that of the loops, and ears or lugs which act as stops to determine the position of the bar and to support it in such position; all of such parts integral with the tension members and the entire bar capable of being stamped or punched from a single piece of metal. Moreover, as already stated, the metal may be punched out so that the strips which constitute the loops and the projecting strips may be given any desired angle to give the proper tension to the bar when the concrete is formed around it, and some of the strips or loops may have one angle and other of the strips or loops may have a different angle or angles, as already shown, and this feature is one of prime importance. Such a bar is obviously of maximum efficiency and may be made at a minimum cost by the method herein described.

If desired, one or more cross rods, as 8, may be provided to assure the retention of the tension members in their proper positions, said cross rods being preferably supported in eyes in the loops 3 and having holding nuts or other suitable fastening means.

It is to be understood that many forms other than those herein set forth, and many apparently widely different variations of the invention may be made within the spirit of the invention as expressed by the subjoined claims, for which reason the forms of the invention herein described, or shown in the accompanying drawings shall be interpreted as illustrative and not as restrictive of the claims.

I desire it also to be understood that the language used in the following claims is intended to cover all of the generic and specific features of the invention herein described and all statements, or matter relating to or bearing upon the scope of the invention which, as a matter of language, might be said to fall therebetween.

Having now described my invention, what I claim as new and desire to secure by Letters Patent is:

1. In a unitary reinforcing means for a concrete or cementitious body the combination with main longitudinal reinforcing bars or tension members arranged on each side thereof, of an open web connecting the same and constituting a series of arched shear members extending transversely from the tension members and engaging flatwise the main body of the concrete, said shear members being fixedly united to said main bars or tension members.

2. In a unitary reinforcing means for a concrete or cementitious body, the combination with main longitudinal reinforcing bars or tension members arranged on each side thereof, of an open web integral with the said tension members connecting the same and constituting a series of arched shear members extending transversely from the tension members and engaging flatwise the main body of the concrete.

3. In a unitary reinforcing means for a concrete or cementitious body, the combination with main longitudinal reinforcing bars or tension members arranged on each side thereof, of an open web integral with and connecting the said tension members constituting a series of arched shear members and strips extending transversely from the tension members and engaging flatwise the main body of the concrete.

4. In a unitary reinforcing means for a concrete or cementitious body, the combination with main longitudinal reinforcing bars or tension members arranged on each side thereof, of an open web integral with and connecting the said tension members constituting a series of arched shear members

extending transversely and strips extending upwardly from the tension members and inclined at an angle each way from the center thereof, and engaging flatwise the main body of the concrete.

5. In a unitary reinforcing means for a concrete or cementitious body, the combination with main longitudinal reinforcing bars or tension members arranged on each side thereof, of a series of transversely extending arched shear members fixedly united to said bars and connecting the same with each other, and strips projecting from said bars and each fixedly united thereto at one end and having its other end free, said arched members and strips being disposed at different places in the lengths of the bars.

6. A reinforcing means for concrete and other material, having its tension member composed of a plurality of elements, loops extending from said elements and connecting the same with each other and strips projecting from said elements and having free ends, said loops and strips being arranged at different angles and fixedly united thereto.

7. A reinforcing means for concrete and other material, having its tension member composed of a plurality of elements having a series of projecting members fixedly united thereto, one or more of said projecting members forming loops which connect the tension members with each other and one or more of the projecting members having free ends.

8. A reinforcing means for concrete and other material, having its tension member composed of a plurality of elements having a series of projecting members formed integral therewith and extending therefrom at different angles, one or more of said projecting members forming loops which connect the tension members with each other and one or more of the projecting members having free ends.

9. A reinforcing means for concrete and other material, having a tension element composed of a plurality of members, and its said members provided with a series of projections some of which have free ends and others of which extend continuously from one of said members to the other.

10. A reinforcing means for concrete and other material, having a tension element composed of a plurality of members, and its said members provided with a series of projections formed integral therewith, some of said projections having free ends and others extending continuously from one of said members to the other.

11. A reinforcing means for concrete and other material, having a tension element composed of a plurality of members and its said members provided with a series of projections which extend therefrom at varying angles, some of said projections having free ends and others being arched and extending

continuously from one of said members to the other.

12. A reinforcing means for concrete and other material, having a tension element composed of a plurality of members, and its said members provided with a series of projections which are formed integral therewith and extend therefrom at varying angles, some of said projections having free ends and others being arched and extending continuously from one of said members to the other.

13. A reinforcing means for concrete and other material, having a tension element composed of a plurality of spaced members, loops or stirrups connecting said members with each other and strips projecting from said members and having free ends, said loops and strips being arranged at different angles.

14. A reinforcing means for concrete and other material, comprising a tension element composed of a plurality of members, loops or stirrups connecting said members with each other, strips extending from said members and having free ends and devices for positioning the reinforcing means.

15. A reinforcing means for concrete and other material, comprising a tension element composed of a plurality of members, loops or stirrups connecting said members with each other, strips extending from said members and having free ends, and devices for positioning the reinforcing means, said positioning devices having laterally and downwardly extending elements.

16. A reinforcing means for concrete and other material, comprising a tension element composed of a plurality of members, loops or stirrups connecting said members with each other, strips having free ends, extending from said members at different angles from the loops or stirrups, and devices for positioning the reinforcing means.

17. A reinforcing means for concrete and other material, comprising a tension element composed of a plurality of members, loops or stirrups connecting said members with each other, strips having free ends, extending from said members at different angles from the loops or stirrups, and positioning devices having laterally and downwardly extending elements adapted to engage sides of a form.

18. In a unitary reinforcing means for a concrete or cementitious body, the combination with main longitudinal reinforcing bars or tension members arranged on each side thereof, transversely extending straps or loops connecting said bars and strips projecting from said bars and having free ends, said straps or loops and strips being arranged alternately along the length of the bar.

19. In a unitary reinforcing means for a concrete or cementitious body, the combina-

tion with main longitudinal reinforcing bars or tension members arranged on each side thereof, of an open web fixedly united with the said tension members, connecting the same and formed to provide a series of arched shear members and strips, arranged alternately, and engaging flatwise the main body of the concrete.

20. In a unitary reinforcing means for a concrete or cementitious body the combination with main longitudinal reinforcing bars or tension members arranged on each side thereof, of an open web connecting the same and formed to provide a series of arched shear members extending transversely from the tension members and arranged at varying distances apart and engaging flatwise the main body of the concrete.

21. In a unitary reinforcing means for a concrete or cementitious body the combination with main longitudinal reinforcing bars or tension members arranged on each side

thereof, of an open web connecting the same and formed to provide a series of arched shear members extending transversely from the tension members and arranged at varying distances apart and at varying angles of inclination and engaging flatwise the main body of the concrete.

22. A reinforcing means for concrete and other material, having its tension member composed of a plurality of elements, and inclined loops connecting said elements with each other and fixedly united thereto and arranged to have flatwise engagement with the main body of the material.

In witness whereof I have hereunto set my hand at the city, county, and State of New York, this 10th day of September, 1906.

JULIAN O. ELLINGER.

In presence of—

JAS. E. PAYNE,
AUGUSTE NAMUR.
